UNITED STATES PATENT OFFICE.

ROBERT BOSCOE, OF CLARENDON HILLS, ILLINOIS, ASSIGNOR TO WESTERN ELECTRIC COMPANY, INCORPORATED, OF NEW YORK, N. Y., A CORPORATION OF NEW YORK.

APPARATUS FOR ABRADING.

Application filed October 7, 1924. Serial No. 742,114.

This invention relates to apparatus for abrading, and more particularly to an apparatus for abrading the surfaces of metal and other articles preliminary to the application of a protective coating thereon.

The primary object of the present invention is to provide an improved apparatus for rapidly and efficiently abrading the surfaces of articles of various shapes and sizes with a minimum amount of manual handling.

Other objects and advantages will become apparent in the following detailed description and the novel features of the invention will be particularly pointed out in the appended claims.

The preferred embodiment of the invention comprises a barrel shaped treating chamber within which one or more blast nozzles are caused to direct abrading material upon the contents contained therein. A loading tray or platform is provided whereby the articles to be treated are introduced into the treating chamber and a dump door is provided whereby the treated articles are ejected from the treating chamber and collected in a suitable receptacle positioned nearby. Means is provided for directing a blast of air upon the treated articles to remove the dust and pulverized blasting material from the surfaces thereof before they are ejected from the treating chamber. The dust and pulverized sand escape through an exhaust cowl or canopy which tops a cabinet inclosing the apparatus and is readily removable therefrom to permit of replacing or repairing the treating chamber.

One embodiment of the invention is illustrated in the accompanying drawings, in which

Fig. 1 is a front elevation, partly in section, of a sand blast apparatus embodying the features of the present invention;

Fig. 2 is a vertical section on the line 2-2 of Fig. 1;

Fig. 3 is a vertical section on the line 3-3 of Fig. 2;

Fig. 4 is an enlarged detail view of one of the blast nozzles;

Fig. 5 is an enlarged detail view of the sand supply fixture;

Fig. 6 is an enlarged detail view of the air and sand control mechanism, and

Fig. 7 is an enlarged fragmentary view illustrating one of the various construction details.

Referring now to the drawings in detail, wherein like reference characters designate corresponding parts throughout the several views, 10 is a sheet steel cabinet within which are enclosed all of the operating parts of the machine. A sand hopper comprising two conical shaped compartments 11, 11, is suitably supported near the bottom of the cabinet 10, and sand from any suitable supply source (not shown) is introduced into each of the compartments 11 through an inlet pipe 12 which is disposed at an angle of approximately 45°. The bottom or reduced portion of the compartment 11 is open and is connected with a housing or sand supply fixture 13.

Rotatably supported in the upper part of the cabinet 10 is a barrel shaped chamber 15 comprising a perforated cylindrical portion 16 and sloped end portions 17 and 18. A removable door 19 forms a part of the cylindrical portion 16 and is provided with a suitable cam latch 20 by which it is securely locked in position. Sand blast nozzles 22 project into the chamber 15 through openings 23 in the end portions 17 and 18 thereof. Each sand blast nozzle 22 is connected to a chambered fixture 24 (Fig. 4), which carries therein an air nozzle 25 which extends a short distance into the sand blast nozzle 22 to give the correct siphoning effect. The sand supply fixture 13 is connected with the fixture 24 by a pipe 21, which at its point of connection with the sand supply fixture 13 is disposed at an angle of approximately 45°, and through which the sand is drawn therefrom to the sand blast nozzle 22. An air agitator nozzle 27 is located within the sand supply fixture 13 and serves to keep the sand therein in a suitable condition to be drawn and also assists in moving the sand therefrom through the pipe 21 to the sand blast nozzle 22. An air supply line 29 is connected with the air nozzle 25 in the fixture 24 and with the air agitator nozzle 27 in the sand supply fixture 13. A water separator 26 of any well known construction is provided in the air line 29 for removing the water therefrom, and a suitable pipe or conduit 28 is provided for draining off the water removed thereby.

An air nozzle 30, independently of the nozzle 22, projects into the chamber 15 through the opening 23, and air flowing therethrough serves to remove the dust and pulverized

sand from the surfaces of the treated articles before they are removed from the treating chamber. A three way valve 32 is provided in the main air line 29 for controlling the 5 air supplied to the air nozzles 25 and 30 and the air agitator nozzle 27. A lever 33 is provided for operating the valve 32 and resiliently supports a member 34 which is adapted to engage either of three notches 35, 10 36 and 37 in a segment 38 whereby the valve 32 may be locked in either of three positions, Fig. 6.

The treating chamber 15 is supported on a pair of idler rollers 39 and a pair of friction drive rollers 40. The idler rollers 39 are keyed to an idle shaft 41 rotatably journaled in bearings 42 and the friction drive rollers 40 are keyed to a shaft 43 rotatably journaled in bearings 44. A sprocket 45 is secured to the end of the shaft 43 and is driven by a chain 46 from a sprocket 47 secured to a main drive shaft 48. The shaft 48 may be driven from any suitable source of power such as an electric motor 49, and a gear reducer of a well known type indicated generally at 50 may be employed to operate the machine at the required speed. The sprockets 45 and 47 and the chain 46 are inclosed in a housing 51 secured to the frame 30 10.

To facilitate introducing articles to be treated into the chamber 15, a tray or loading platform 55 is provided which is hinged at 56 to the frame 10 so that it may be 35 moved to the position wherein it is shown in dotted lines in Fig. 2, when the door 19 is removed from the chamber 15. The loading platform 55 is provided with side members 57 which serve to prevent articles from 40 falling therefrom during the loading operation into the lower portion of the inclosing cabinet and thus interfere with the operating parts of the machine.

Suitably supported directly below the 45 treating chamber 15 and disposed at an angle of approximately 45° is a perforated steel plate 60 which is in alignment with a dump chute 61 secured to the frame 10. A dump door 62 is hinged at 63 to the frame 10 50 and opens inwardly to provide an unrestricted passage for the ejected articles between the plate 60 and chute 61. The dump door 62 is operated by a lever 64 positioned at the side of the cabinet 10 within convenient reach of the operator. A rubber sheet 65 secured to the inner side of dump door 62 serves to prevent the escape of sand 55 from the cabinet 10.

The cabinet 10 is topped by an exhaust 60 cowl or canopy 70 which is secured to the cabinet and to exhaust pipes 71 by eyebolts 72 so that it can quickly be disconnected and removed when it is necessary to replace or repair the treating chamber 15. A door 74 65 is provided in the front side of the cabinet

10 and is adapted to be elevated in suitable guide ways 75 to expose the treating chamber 15 during the loading and unloading operations. The door 74 is suspended by cables threaded over pulleys 76 supported by a horizontal I-beam 77 and connected to balancing weights 78 to facilitate the opening and the closing thereof.

When loading the treating chamber 15, the door 74 is elevated in the guide ways 75 and the door 19 is removed from the chamber 15 to provide an opening therein for the insertion of the articles to be treated. The loading platform 55 is then swung inwardly so that it rests on the lower lip of the opening in the treating chamber to permit sliding the articles therein. When the treating chamber has been loaded, the door 19 is locked in place and the door 74 is closed. The apparatus is now ready for the sand blasting operation.

Upon starting the electric motor 49 to rotate the treating chamber 15, the lever 33 is moved to the notch 35 in the segment 38 which operates the valve 32 to start the sand blasting operation (see Fig. 6). The rotation of the barrel shaped treating chamber causes a rotary movement of the articles being treated and the sloped ends of the chamber causes a longitudinal movement thereof. After the articles have been treated the lever 33 is moved to the notch 36, at which position a current of clean air is directed against the treated articles through the nozzle 30, thereby removing the dust and pulverized sand from the surfaces thereof. The dust and pulverized sand escape through the exhaust cowl 70 and the spent sand escapes through apertures 80 in the treating chamber and re-enters the compartment 11 through a steel screen 81 covering the top opening thereof.

After the dusting operation, the valve 32 is closed and the treated articles are ready to be removed from the treating chamber. The door 74 is opened, the door 19 is removed, and the dump door 62 is swung inwardly to form an unrestricted passage with the steel plate 60 and the chute 61. The treating chamber is then rotated, causing the treated articles to drop through the opening therein, falling upon the steel plate 60 and dump door 62 and sliding down the chute 61 into any suitable receptacle positioned nearby.

What is claimed is:

1. In an abrading apparatus, a compartment, a treating receptacle housed by the compartment containing an article to be treated, a nozzle arranged within said compartment and extending into the receptacle for directing abrading material upon the surfaces of the article, and a second nozzle positioned within the other nozzle for directing a gaseous medium upon the surfaces

of a treated article to remove the loose material therefrom after the article has been abraded while confined within said receptacle.

5. 2. In an abrading apparatus, a cabinet, a treating receptacle enclosed by the cabinet and housing an article to be treated, a chute permanently attached to the cabinet and movable to a position for introducing articles into the treating receptacle, a nozzle 10 extending into the treating receptacle for di-

recting abrading material upon the surfaces of the article, and a second nozzle positioned within the other nozzle for directing a gaseous medium under pressure upon the 15 surfaces of a treated article to remove loose material therefrom after the nozzle has been abraded.

In witness whereof, I hereunto subscribe my name this 26th day of September A. D., 20 1924.

ROBERT ROSCOE.
